UNITED STATES PATENT OFFICE.

HERSCHEL TUPES, OF THE UNITED STATES ARMY, AND HAYNES E. HARRELSON, OF SAMAR
PHILIPPINE ISLANDS; SAID HARRELSON ASSIGNOR TO SAID TUPES.

GUN-CLEANING DEVICE.

No. 921,569.

Specification of Letters Patent.

Patented May 11, 1909.

Application filed August 26, 1907. Serial No. 390,236.

To all whom it may concern:

Be it known that we, HERSCHEL TUPES, a captain in the U. S. Army, and HAYNES E. HARRELSON, residing at Samar, Philippine Islands, citizens of the United States, have invented certain new and useful Improvements in Gun-Cleaning Devices; and we do hereby declare the following to be a full, clear, and exact description of the invention, such as will enable others skilled in the art to which it appertains to make and use the same.

Our invention relates to an improvement in gun cleaning devices for removing lead, rust, metal fouling, powder fouling and other substances that may accumulate in the bore of guns and small arms.

It is a known fact, that in practice, it is a difficult matter to remove lead, rust and other substances from the bores of guns and small arms, and it is the object of our invention to overcome the above and to provide a device which will not wear out easily and which can be cheaply manufactured and to these ends our invention consists essentially in providing a helical spring adjustably mounted on a rod, the whole forming the head member, and a handle member of our gun cleaning device.

Referring to the drawings forming part of this specification; Figure 1 represents a side elevation of our device showing the handle member broken away; Fig. 2, an enlarged longitudinal section of the cleaner head with the handle removed, and Fig. 3, a modified form of device.

Like letters of reference represent like parts in all the views.

A represents a metal rod, threaded at one end, as at B, and having a shoulder C of less diameter than the gun barrel at its other end. An internally threaded sleeve or nut D is mounted on the rod A near one end and is adapted to be screwed back and forth on the same. Surrounding the rod A is a helical spring E, made preferably of steel, spring brass, or other suitable material, and having one end bearing against and attached to the shoulder C, and the other end attached to a washer F which bears against the nut D. G represents a threaded stud which screws into

the threaded socket H of a handle I. The handle I is preferably made in sections so that the cleaner head K can be used in long and short barrels of guns and small arms. 55

In cleaning lead, rust and other substances from the bores of guns and small arms, it is essential that care be taken not to injure the rifling as this is often done by the use of cleaners and scrapers that are now in use. With our device, it will be seen that by simply turning the sleeve D to the right or left, the diameter of the helical spring E can be changed at will, thereby assuring a good contact with the rifling, 60 and at the same time regulating the amount of friction between the cleaner and rifling. Besides, if the cleaner is made of spring brass the metal is so much softer than the rifling that no injury whatever results. 70

The modified form of device shown in Fig. 3 consists of a smooth rod or core A' provided with shoulders C' and D'. Surmounting the rod or core A' is a helical spring E' held against longitudinal movement by the shoulders C' and D'. The core or rod A' has an enlarged end F', perforated as at G', to which can be attached a wire or other flexible handle (not shown). In the modified form no means are shown to 80 adjust the spring E', but in manufacture, the spring in this form may, if desired, be made of softer and finer material so as to prevent injury to the rifling, or it may be made like the form shown in Fig. 1. 85

In operation the spring E of the cleaning device is adjusted to form a good contact with the bore of the gun. The head K is then inserted into the barrel and reciprocated by means of the handle member I. 90 This is repeated until all the rust, etc. has been removed.

What we claim as our invention and desire to secure by Letters Patent, is:—

In a gun cleaning device, a cleaning head 95 comprising a core A threaded at one end only and having the shoulder C at the other end; a helical cone shaped spring made of a material softer than that of the rifling in the gun to be cleaned and surmounting said core; an abutting washer through which one end of said spring passes, and having a hole 100

larger than said screw threaded core which it surrounds, a nut on said core contacting with said washer for adjusting said spring, said threaded end extending beyond said 5 nut; and a threaded handle attached to the said extended end of the core member, substantially as described.

In testimony whereof, we affix our signatures, in presence of two witnesses.

HERSCHEL TUPES.

HAYNES E. HARRELSON.
